PACKAGE AND LIKE BINDING MECHANISM

Frederick William Mosey, London, England

Application September 5, 1951, Serial No. 245,220

16 Claims. (Cl. 100—31)

This invention is particularly concerned with that type of package and like binding mechanism adapted to use a continuous flexible element from a supply and essentially comprising a connecting device for overlapping portions of a loop of the said element around the package or the like, means for severing the portion of the element extending to the near side of the said connecting device from the said supply to form an end portion of the element and means for projecting this end portion lengthwise for loading i. e. insertion or threading into the said connecting device for the next operation.

In one known arrangement such loading has been effected by projecting this free end lengthwise of the element directly into the connecting device. A principal object of the present invention is so to modify this arrangement as to render the loading more certain, from which aspect the invention provides for the free end to be projected to overlap the connecting device and for the element then to be loaded therein by relative transverse movement between the projected portion and the said device.

The end portion of the flexible element may thus be projected into a position out of the binding planes adjacent, e. g. in front of, a connecting device in the said plane and can then be loaded transversely into the said device by movement more or less perpendicularly to the plane.

The loading of the flexible element into the connecting device may conveniently be effected manually as the first step of the operating cycle of the apparatus.

The end of the flexible element is preferably projected past and beyond the connecting device, there to be engaged by means adapted to draw back and load the flexible element into the said device, for which purpose the apparatus may include on the far side of the connecting device, a holding gripper which when open is adapted to receive the projected end of the flexible element and by closing of which the element is thus loaded.

Deflecting means may be provided on the near side of the connecting device for guiding the free end of the flexible element past the latter and adapted to be retracted before or during the loading of the element into the said device.

The return movement of a gripper which at severing is left engaging the free end of the flexible element on the near side of the connecting device, may be used for projecting the said free end. As the stroke needed for such projection will in general considerably exceed that for tensioning, a gripper used to tension is usually not suitable for this purpose and the present invention from this further aspect therefore provides, in the aforementioned type of apparatus, on the near side of the connecting device, a combination of grippers movable differentially away from and towards the latter, one for tensioning the loop of the flexible element around the package or the like by a relatively short outward stroke and the other for projecting the severed end portion of a relatively long inward stroke, each gripper being adapted to

2

permit passage of the element during the operative stroke of the other. The short stroke gripper is preferably arranged inwardly of the long stroke gripper, the two grippers being shiftable simultaneously so as to separate as they move outwardly and to approach one another as they return.

The gripper or each of the grippers used for tensioning and/or projection, can conveniently be mounted on a lever arm adapted to be swung towards and away from the connecting device.

In apparatus for binding with wire and having the usual slotted twisting pinion type of connecting device, the wire end may first be projected on the near side of the connecting device, which is of the pinion type so that the wire extends beside and preferably beyond the opposite or far side and in the plane of the slot of the device when it is in its position of rest, the wire then being moved transversely by means adapted to engage the projected end and to draw it towards the axis of said device to thread the wire into the slot thereof. The use of the terms "near side" and "far side" is with reference to the sides (or ends) of the twisting pinion of the device and that end of the binding wire which is projected past or beyond said pinion in the operation of the apparatus.

The wire may thus be projected angularly with respect to and preferably across the axis so as to incline away therefrom as it passes the pinion of the device. Projection of the wire end thus across the axis may be effected by mounting a gripper used for such projection on a swinging arm as hereinbefore suggested, in such a way that the gripper is moved away from said axis as the arm swings outwardly and towards said axis as the arm swings inwardly.

The apparatus according to the invention is particularly suitable for partially automatic operation according to a cycle wherein, following closing of a far side holding gripper with consequent loading of the flexible element into the connecting device, the element is manually trained by looping it about the package or the like back through the connecting device and into near side tensioning and projecting means, prior to completion of the cycle automatically.

The foregoing and other features of the invention will now be described as embodied in the partially automatic wire binding machine apparatus shown in the accompanying drawings whereof:

Fig. 1 is a top plan view of the main operating mechanisms of a package or like binding apparatus embodying the preferred form of the invention, which mechanisms are disposed beneath the package supporting top plate of the apparatus, a part of which plate is broken away from better illustrative purposes.

Figures 1A, 1B and 1C are diagrams to show the movements of the main mechanisms of the apparatus during an operating cycle;

Figures 2A and 2B are vertical sectional views through a part of the apparatus as taken on the line 2A—2A on Fig. 1 and show, in side elevation, the left hand (far side) holding gripper and its operating means with the 60 gripper respectively closed and open;

Figure 3 is a plan view (beneath the top plate or table) of the assembly comprising the connecting device and severing means and the right hand (near side) deflecting guide finger with their operating means;

Figure 4 is a side elevation, partly in section, of the same assembly omitting the guide finger and associated parts but including its operating cam;

Figures 5A and 5B are vertical sectional views as taken on the line 5A—5A of Fig. 1 and show in side elevation the said guide finger and its operating means, with the finger respectively retracted and projected;

Figures 6A and 6B are front elevation and plan views

3

(beneath the top plate or table) respectively of the right hand tensioning and projecting gripper assembly, and Figure 6C a section along the line 6c—6c of Figure 6B showing the tensioning gripper opened.

As can be seen from Figures 1, 1A, B and C, the general lay-out of the apparatus follows the well known standard practice in which an assembly 1, comprising a twisting pinion connecting device 1a and cutter 1e and 1f blades, near each side or end of the pinion, is associated with a holding gripper 2 as little removed as practicable beyond the cutter to the left, when facing the front of the machine (hereinbefore called the far side of the connecting device) and a tensioning gripper 3 at a sufficient distance out beyond the cutter to the right (hereinbefore called the near side of the connecting device) to clear the package for convenience in training of the wire into this gripper.

The training of the wire around the package or the like is carried out manually, Figure 1A showing it fully 20 trained with the wire end w1 held by gripper 2, from which the wire extends through the twisting pinion, being continued thence as wire part w2 looped around the package back oppositely through the pinion from which wire part w3 extends to gripper 3 and is continued beyond as wire part w4 to the supply coil (not shown).

The present machine has as special additional features, firstly a guide finger 4 close in to the cutter to the right for engaging wire part w3 when severed and positively for deflecting it clear of the connecting device assembly for projection past it as the new wire end w1, and secondly an additional right hand gripper 5 out beyond, and with a longer stroke than, gripper 3 for engaging the wire part w4 and moving therewith, thus to project the wire further than would be possible by relying on the return stroke of gripper 3 for this purpose.

These various mechanisms are arranged in the customary manner along and just below the front edge of a package-supporting top plate or table 6 not shown in Figures 1A, 1B and 1C but appearing in certain of the other figures.

After the wire has thus been trained and gripper 3 closed on to wire part w3 this gripper is moved outwardly as indicated in Figure 1A, thereby to tension the loop w2 whilst gripper 5, which is moved simultaneously and in the same direction as gripper 3, is able to move out along wire part w4.

The connecting and severing assembly 1 is then operated in the usual way to leave the wire as shown by the full lines in Figure 1B. Thereupon gripper 2 is opened and guide finger 4 is projected to positions indicated in this figure, thereby respectively releasing the wire end tailing w1 and deflecting the severed wire part w3 forwardly.

Next grippers 3 and 5 are returned inwardly to their normal positions as shown in Figure 1C, this time with gripper 5 in operative engagement with wire part w4 and with gripper 3 open so that wire part w3 is able to pass through it.

As a result of the stroke of gripper 5 being longer than that of gripper 3, wire part w3 when thus taken over by the former, becomes projected, deflected positively under the guidance of finger 4, past the twisting pinion assembly 1 in front of the slot in the pinion, which is directed horizontally outwards when the pinion is at rest, into gripper 2, the opening of which is sufficient to enable it to receive the wire end thus projected. This considerable range of gripper 2 for the purpose of engaging the wire end is a further special feature of the present invention.

Finally finger 4 is either retracted or released for retraction by the wire as it is loaded by being drawn back into the twisting pinion. This last mentioned operation is effected by the closing of gripper 2, which step may be arranged to conclude the binding cycle. It can, however, alternatively be carried out manually by the operator's left hand, to which this gripper is conveniently accessible,

as the first step of the following cycle, thereby making it possible to avoid the use of the customary fingers or like members for ejecting the tied connection from the twisting pinion, since the bound package is removed before the projected wire end is loaded into the pinion.

Following the closing of gripper 2 and the holding of the wire end w1 and loading of wire part w3 into the twisting pinion consequent thereon, the operator, with his right hand, proceeds to remove the wire from grippers 3 and 5, loops the wire around the package, threading it again into the pinion, and then into grippers 3 and 5 ready for completion of the cycle automatically. This automatic portion of the tensioning, connecting, severing, deflecting, gripper opening and projecting sequence may be initiated from a manual control conveniently accessible to the right hand of the operator as he completes the manual training with that hand, or in the form of a pedal.

The automatic portion of the sequence is power operated from a continuously rotating motor through a single operation clutch which is adapted to be tripped by the aforementioned right hand manual control, none of which parts are however illustrated as they are preferably standard. Tripping of this clutch results in a single rotation of the main cam shaft 7 which extends beneath the top plate 6 parallel with the front edge thereof and behind the mechanisms before mentioned and which are required to be operated, the power input from the clutch being applied to the shaft at gear 7a (see Figures 6A and B) thereon. One particular apparatus adapted for driving the binding apparatus in the intermittent manner above described is disclosed in Harvey Patent No. 2,134,187.

The actuation of the individual devices or mechanisms will next be described, starting from the left hand end.

Referring firstly to Figures 2A and 2B, the holding gripper 2 comprises a rear fixed jaw 2a and a forward movable jaw 2b adapted to be projected automatically by the high part of cam 2c acting through the follower roller 2d on lever 2e against tension spring 2f, to release the wire end tailing w1 and to leave the jaw 2b fully projected as shown in Figure 2B for the reception of the fresh wire end.

Retraction of jaw 2b to close the gripper is effected under manual control of a ratchet lever and gear arrangement including a lever handle 2g pivoted coincident and movable together with a pinion 2h adjacent a fixed ratchet segment 2i. This pinion meshes through another pinion 2j with the toothed underside of said jaw. A spring pressed pawl 2k is so pivotally mounted on said lever as to engage said ratchet segment for holding said jaw projected until the pawl is lifted by grip 2l, which is also pivoted on the lever, to permit lowering of the latter and retraction of the said jaw, under the influence of the said spring 2f, to the position shown in Fig. 2A. The cam 2c is so contoured as not to interfere with full such closing of the gripper immediately the high part of the cam has passed roller 2d.

If it is desired to actuate gripper 2 entirely automatically, the manual control and its associated gear may be omitted, without alteration of the timing of the cam, the high part of which must in any case have cleared roller 2d before the rotation of shaft 7 is completed.

Turning now to the construction and operation of the connecting device and cutter blade assembly shown in Figures 3 and 4, the twisting pinion 1a is actuated in the ordinary well known manner through a gear train 1b, 1c, from a toothed quadrant 1d on shaft 7 adapted to come into effective operation following tensioning of the wire to impart to the pinion the required number of turns, say three, and a fraction over for overtwist. The respective cutter blades 1e and 1f are mounted at the top of spring-loaded plungers 1g vertically movable one at each end of the twisting pinion, the blade 1e on the far side of the connecting device adapted to sever the wire part w1 which is rearwardly placed within the pinion and the blade 1f on the near side of said device the forwardly placed

wire part w_3 . The two plungers $1g$ are adapted to be lifted together on completion of the twisting pinion actuation, by lug $1h$ on shaft 7 engaging and rocking lever $1i$, the forward end of which is connected with the plungers through the cross rod $1j$ between them.

Referring still to Figure 3, but now in conjunction with Figures 5A and B, guide finger 4 is adapted when retracted to leave the wire parts w_2 and w_3 entirely free but when extended to engage part w_3 within slot $4a$. The movement of finger 4 is simply controlled from cam $4b$ on shaft 7 through follower roller $4c$ on lever $4d$ against tension spring $4e$. If the latter is omitted the transverse loading movement of wire part w_3 may be sufficient to draw back the finger but cannot be relied on to do so fully.

It now remains to describe the right hand gripper assembly with reference to Figures 6A, B, and C. The tensioning gripper 3 and the projecting gripper 5 are each respectively mounted on a lever arm $3a$ and $5a$, the former arranged inwardly of the latter, that is, closer to the connecting device than the latter. These arms are independently pivoted to swing horizontally beneath the level of the top plate 6 and in their normal positions to extend in substantial parallelism with one another and substantially perpendicularly to the binding plane. Gripper 3 is adapted to engage the wire only as its arm $3a$ swings outwardly away from the connecting device and similarly gripper 5 is adapted to engage the wire only as its arm $5a$ swings inwardly toward the connecting device.

The two arms $3a$ — $5a$ are required to be swung simultaneously by means such that the amplitude of swing of arm $5a$ is greater than that of arm $3a$. The grippers consequently separate from one another as the arms swing out away from the connecting device and collapse together as they return, thus enabling gripper $5a$ to take a hold on the wire sufficiently far out to return it through the required greater distance than that through which it was moved in tensioning.

The means for thus swinging the arms consists of cam $3b$ on shaft 7 . Roller $3c$ on the intermediate horizontally swinging lever $3d$ is adapted to follow the cam groove whereby this lever is moved positively in both directions. A link $3e$ extends from the forward end of the lever into telescopic relationship with the collar $3r$ and is held therein by pin $3p$. The collar $3r$ is connected to the gripper arm $3a$ and incorporates a compression spring $3f$ between threaded members $3g$ and collar $3r$ to cushion the tensioning stroke of the latter subject to adjustment by the rotatable threaded member $3g$. By arranging link $3e$ well forwardly toward the free end of gripper arm $3a$ a relatively short stroke is imparted to the latter. The link $5b$ from lever $3d$ to arm $5a$ is on the other hand arranged further back on the arm toward the pivot $5c$ to impart a relatively long stroke to the latter. This differential effect can be increased by making arm $5a$ shorter than arm $3a$, the pivot $5c$ about which arm $5a$ swings being positioned forwardly of the pivot $3h$ of arm $3a$ to maintain grippers 3 and 5 in alignment when arms $5a$ and $3a$ are substantially parallel.

The tensioning gripper 3 is adapted to be opened positively just before severing of the wire part w_3 , mainly to avoid the buckling of the wire between grippers 3 and 5 which might otherwise occur due to the variable extent of the outward jump of the former towards the latter under the influence of spring $3f$ according to the applied tension, immediately severing takes place. It is an added advantage for gripper 3 to continue to be held open positively in order to ensure free feeding of wire through it by gripper 5 during the return of the arms and to facilitate the subsequent removal and insertion of the wire when training it from and into gripper 3 .

The opening and closing of gripper 3 is controlled in this way from cam $3i$ on shaft 7 for engagement with which a tail $3j$ of the lower jaw $3m$ of the gripper is extended downwardly and also laterally to banjo form to cover the range of the outward swing of arm $3a$. It will

be noted that the edge $3k$ which follows the cam is curved to correspond with this swing. The high part of the cam acts to thrust open jaw $3j$ against tension spring $3l$, this cam being timed so that the gripper is permitted to close at the beginning of the automatic sequence just before cam $3b$ starts to operate and is opened immediately before severing. Instead of laterally extending jaw $3j$ to cover the swing of arm $3a$, cam $3i$ might be correspondingly extended and shaped.

Reference to Figures 1A and 1B will make clear that by mounting grippers 3 and 5 on arms adapted to swing back behind the axis of the twisting pinion and therefore behind the binding plane, the severed wire part w_3 tends to be directed by gripper 5 angularly across the said axis and plane in front of the pinion in the required manner, guide finger 4 providing proper support for the wire adjacent the pinion to ensure that it shall in fact pass the latter as required.

It is enough for gripper 5 to be of a simple type adapted to hold the wire lightly and capable of sliding outwardly along it, with provision as shown for manual opening for purposes of wire training. Alternatively opening and closing of gripper 5 may be effected automatically as it approaches and leaves its normal position, e. g. by abutment against gripper 3 , but this arrangement suffers from the disadvantage that gripper 5 is not then available for holding the projected wire end before closing of gripper 2 . The gripper 5 comprises a serrated jaw $5d$ pivotally mounted about pivot $5e$ to engage upper jaw $5f$ and clamp a binding element therebetween during the projecting stroke. Coil spring $5g$ engages manual control $5h$ to urge the jaws into engagement. During tensioning, however, the binding element will freely slide between the jaws. Automatic operation of jaw $5d$ is effected by engagement of rod $3n$ therewith, though this is not essential, as described above.

What I claim is:

1. In a package or like binding apparatus, means for connecting two portions of a loop of flexible binding element around the package or the like, means for severing the said element extending to the near side of said connecting means from a supply to form an end portion, means for projecting said supply end portion lengthwise for operative engagement with said connecting means, said projecting means including a pair of grippers which remain between said severing means and said supply, and means for moving said grippers simultaneously outwardly from and inwardly towards said connecting means, one of said grippers being operative to grip said element during its outward stroke which is relatively short for tensioning said loop onto the package or the like, and the other of said grippers being operative to grip said element during its inward stroke which is relatively long for effecting said projection of said supply end portion, each said gripper being adapted to permit passage of the element during its opposite stroke.

2. Apparatus as set forth in claim 1, wherein said short stroke gripper is arranged between said connecting means and said long stroke gripper, and said means for moving said grippers simultaneously is adapted to separate said grippers during their outward stroke and to cause them to approach each other during their inward stroke.

3. Apparatus as set forth in claim 1, wherein each of said grippers is mounted on a lever arm and said means for moving said grippers simultaneously is operative to swing said arms towards and away from said connecting means with said short and long strokes respectively.

4. Apparatus as set forth in claim 3, wherein said means for swinging said lever arms engages said long stroke lever and includes a third lever connected to both said arms, the connection between said third lever and said short stroke arm including resilient means for cushioning the outward tensioning stroke of the latter.

5. In a package or like binding apparatus, means for connecting two portions of a loop of flexible binding ele-

ment around the package or the like, means for severing said element extending to the near side of said connecting means from a supply to form an end portion of said element, gripper means for projecting said supply end portion lengthwise and movable outwardly from and inwardly towards said connecting means while remaining between said severing means and said supply, said projecting gripper means being operative during its inward stroke to grip and effect such projection of said supply end portion into an overlapping laterally spaced relation with said connecting means, and means for moving said supply end portion when thus projected laterally with respect to said connecting means for loading it into operative position therein.

6. Apparatus as set forth in claim 5, wherein said projecting gripper means includes gripping portions to continuously engage the supply end portion and to retain said supply end portion after an operation of said severing means.

7. Apparatus as set forth in claim 5, including means for direct manual control of said means for causing said lateral loading movement.

8. Apparatus as set forth in claim 5, wherein said projecting gripper means includes a pair of grippers and means for moving them simultaneously both outwardly and inwardly, one of said grippers being operative to grip said element during its outward stroke which is relatively short for tensioning said loop onto the package or the like, and the other of said grippers being operative to grip said element during its inward stroke which is relatively long for effecting said projection of said supply end portion, each said gripper being adapted to permit passage of the element during its opposite stroke.

9. Apparatus as set forth in claim 5, wherein said projecting gripper means includes tensioning means operative during its outward stroke to engage said element and to tension said loop onto the package or the like.

10. Apparatus as set forth in claim 5, wherein said projecting gripper means includes directing means to direct said supply end portion out of the binding plane of said loop during said inward stroke.

11. Apparatus as set forth in claim 5, wherein said means for causing said lateral loading movement consists of a holding gripper on the far side of said connecting means, laterally shiftable between an open and an aligned closed position, which holding gripper is adapted when open to receive said supply end portion and in closing thereon to move it laterally as required.

12. Apparatus as set forth in claim 5, wherein said means for causing said lateral loading movement is adapted to engage said supply end portion beyond said connecting means.

13. Apparatus as set forth in claim 12, including means between said severing means and said projecting gripper means movable into operative position for guiding said supply end portion into said overlapping laterally spaced relation with said connecting means.

14. In a package or like binding apparatus, means for connecting two portions of a loop of flexible binding wire around the package or the like and including a rotatable twisting pinion having a wire receiving slot, means for severing said element extending to the near side of said pinion from a supply to form an end portion of said wire, gripper means for projecting said supply end portion lengthwise and movable outwardly from and inwardly towards said connecting means while remaining between said severing means and said supply, said projecting gripper means being operative during its inward stroke to engage and effect such projection of said supply end portion into an overlapping laterally spaced relation with said connecting means opposite said slot when said pinion is at rest, and means for engaging said supply end portion when thus projected and drawing it laterally towards the axis of said pinion for loading it into operative position within said slot.

15. Apparatus as set forth in claim 14, wherein said projecting gripper means is adapted to direct said supply end portion across said axis so that it inclines away from said pinion as it passes the latter.

16. Apparatus as set forth in claim 15, wherein said projecting gripper means is associated with a lever arm whereby said supply end portion is caused to be so directed by said gripper means as said arm swings towards said pinion.
